DESIGN FOR A PICTURE VIEWER

Gifford M. Mast, Davenport, Iowa, assignor to
Tru-Vue, Inc., Rock Island, Ill., a corporation
of Illinois

Application May 27, 1948, Serial No. 146,641

Term of patent 14 years

(Cl. D61—1)

To all whom it may concern:

Be it known that I, Gifford M. Mast, a citizen of the United States, residing at Davenport, in the county of Scott and State of Iowa, have invented a new, original, and ornamental Design for a Picture Viewer, of which the following is a specification, reference being made to the accompanying drawings, forming a part thereof.

In the drawings:

Fig. 1 is a front elevational view of a picture viewer, showing my new design;

Fig. 2 is a top plan view of Fig. 1;

Fig. 3 is a rear elevational view of Fig. 1 but in an inverted position; and

Figs. 4 and 5 are side elevational views of the same from opposite sides.

I claim:

The ornamental design for a picture viewer, substantially as shown.

GIFFORD M. MAST.
